UNITED STATES PATENT OFFICE.

PETER PAUL KELLER, OF KNOXVILLE, TENNESSEE.

ADJUSTABLE HANGER FOR INCANDESCENT LAMPS.

SPECIFICATION forming part of Letters Patent No. 727,150, dated May 5, 1903.

Application filed June 18, 1902. Serial No. 112,187. (No model.)

To all whom it may concern:

Be it known that I, PETER PAUL KELLER, a citizen of the United States, residing at Knoxville, in the county of Knox and State 5 of Tennessee, have invented a new and useful Adjustable Hanger for Incandescent Lamps, of which the following is a specification.

This invention is an adjustable hanger for incandescent lamps, the object being to provide 10 a simple and inexpensive appliance which can be connected to the circuit-wires suspending an ordinary incandescent lamp by means of which the lamp can be raised or lowered, as desired, the circuit-wires being wound upon a 15 drum contained within a casing.

The invention consists in the novel features of construction and combination, all of which will be fully described hereinafter and pointed out in the claim.

20 In the drawings forming part of this specification, Figure 1 is a perspective view showing the adjustable hanger connected to the circuit-wires suspending an ordinary incandescent lamp. Fig. 2 is a view showing one 25 side of the case removed. Fig. 3 is a transverse vertical section taken through the hanger, certain parts being shown in elevation.

Referring to the drawings, A indicates the 30 circuit-wires twisted together, B the ordinary socket, and C the ordinary incandescent lamp connected thereto.

A casing D, essentially circular in shape, is 35 constructed of two sections connected together at the upper and lower ends, said upper and lower ends being shaped into guide portions D' to guide the wire in and out of the case, and an insulating-bushing E is arranged between the sections of the case for 40 the purpose of securely insulating the wire from the said case. A shaft F is arranged within the case, the ends F' being polygonal in cross-section, and thereby held against rotation within the case. A drum G is loosely 45 mounted upon the shaft F; said drum having guide-flanges G' at each side. The strands of the wire A are connected to the drum at two points by means of staples G², said wire being so connected that when the drum is re- 50 volved in one direction the wire will be wound thereon from each end, and when the drum is revolved in the opposite direction the wire will be unwound or reeled off in opposite direction or toward each end. In order to so op-

erate the drum, I employ a flat convolute 55 spring H, one end of which is rigidly connected to the shaft F and the other end connected to the drum G, it being understood that the said spring is arranged about the shaft within the drum, and when the drum 60 is revolved in one direction the spring will be wound up, and the reflex action of said spring will serve to revolve the drum in the opposite direction. In order to lock the drum at any desired point, and thereby provide for 65 adjusting the lamp to any desired height, I employ a ratchet-disk I, which is fixed upon the drum G between the drum and side of the case, and pivoted to the side of the case and adapted for engagement with the ratchet- 70 disk is a pawl K, said pawl being adapted to engage the ratchet-disk whenever the revolution of the drum is checked. It will thus be seen that when it is desired to raise or 75 lower the lamp it is only necessary to pull down upon the wire sufficiently to disengage the pawl, and then the drum can be revolved in the desired direction to either wind or unwind the wire, so that the lamp is raised or lowered, as required, and after the desired 80 adjustment has been obtained the pawl will drop back into engagement with the ratchet-disk, and thereby hold the hanger in a fixed 85 position.

It is obvious that the hanger can be made 90 of any desirable material and any suitable shape, and it will also be understood that certain changes or alterations can be made both in the construction or arrangement of the various parts without departing from the principle of my invention.

Having thus fully described my invention, what I claim as new, and desire to secure by Letters Patent, is—

In an adjustable hanger, the combination 95 with a casing, a revoluble drum mounted therein, a suspending-cording extending through the casing; said cording comprising two twisted members or strands, one strand passing around one side of the drum and the 100 other around the opposite side of the drum, and means for locking the drum against rotation.

PETER PAUL KELLER.
